UNITED STATES PATENT OFFICE

MARTIN P. LUTHER, OF CHICAGO, ILLINOIS, ASSIGNOR TO SUPER SAFETY SWITCH CO., OF CHICAGO, ILLINOIS, A CORPORATION OF ILLINOIS

ELECTRIC SWITCH

Application filed April 2, 1930. Serial No. 440,992.

My present invention relates to switches and particularly to those known as the multiple type and in which a plurality of circuits are opened or closed by a movement of a common operating mechanism and handle.

One of the principal objects of my invention is to provide a switch and switch operating mechanism that is possessed of a high degree of safety whereby the fuses may be readily removed or replaced without the danger present in switches which are now available. The present structure is arranged in such manner that it is impossible to touch any of the live parts of the switch when the door or cover is open, but in addition to this factor the disposition of the parts is such that in the event the cover or door should be accidentally or inadvertently opened or be removed the live parts of the switch are protected in such manner that it will be difficult, if not impossible, for a person to become harmed.

I have also provided substantial insulation within the box between the switch parts and the walls of the box that completely insulate this structure and in addition thereto insure against fire due to a sparking or arcing of the contact members when being pulled apart. This prevents the current flashing through the housing or box during an operation of the switch.

In addition to the foregoing it is an object of my present invention to provide a switch box and switch parts, the arrangement of which is such that an area of considerable extent is provided to accommodate the wiring, and the parts of the switch and their operating mechanism is so compact that they occupy only a small space, thus permitting of a reduction of the dimensions of the switch box or housing.

I have also provided a novel manner of supporting and insulating the stationary and movable parts of the switch, the construction and arrangement of which is such that it is not necessary to provide a box or housing of unusual or special shape and thus permits the use of the enclosure of a true rectangular form.

In the arrangement heretofore mentioned I have mounted the terminals and the sta-

tionary members of the switch close to the sides and back of the housing or box which permits the intervening space to be occupied by conductors or wires, and also allows the ordinary fuses being placed in approximately a horizontal position and extending across the box where they are convenient to handle.

After an understanding of my invention is had it will be obvious that numerous other objects and advantages are incorporated in the structure. I prefer to carry out my invention and to accomplish the numerous objects thereof in substantially the manner hereinafter fully described and as more particularly pointed out in the claims. Reference will now be made to the accompanying drawings that form a part of this specification, in which drawings:

Figure 1 is a front plan view of my improved switch, the central portion being shortened by breaking it away, and the cover or door is opened or removed.

Figure 2 is a longitudinal section of my improved switch, the view being taken on line 2-2 of Figure 1 looking in the direction of the arrows.

Figure 3 is a fragmentary section taken on line 3-3 of Figure 1 and looking in the direction of the arrows, the parts of the switch being opened, and,

Figure 4 is a view similar to Figure 3 except that the parts of the switch are shown closed.

Figure 5 is a transverse section taken on line 5-5 of Figure 2 and drawn to a larger scale to illustrate the formation and mounting of the operating bar and one of the insulating housings for the stationary contact element.

Figure 6 is a section on line 6-6 of Figure 2 looking in the direction of the arrows and showing the parts illustrated in Figure 5 in vertical section.

Figure 7 is a sectional view of the operating bar and showing one of the movable contacts and a fuse-carrying clip or yoke.

The drawings, it will be understood, are more or less schematic and are intended to disclose a typical or preferred embodiment of my invention, and in said drawings I have

employed similar reference characters to designate like parts whereby they occur throughout the various figures.

As heretofore stated, my switch is of the inclosed or housed type and is therefore enclosed within a sheet metal box. This box consists of longitudinally disposed parallel side walls 10 and 11 that are connected at their ends by transverse walls 12 and 13, and 10 their longitudinal rear edges are connected by a back or rear wall 14 so that a true rectangular shaped structure is provided, that is open at its front.

For the purpose of closing the front of the 15 box I provide a cover or door 15 that has lateral flanges 16 along its edges that overlap the edges of the box, and said cover is mounted upon the longitudinal wall 11 by means of hinges 17. A transverse spring plate 18 is 20 secured to the wall 10 and enters a slot in the adjacent portion of the door when the latter is closed. This plate is provided with a latching spur 19 to release the cover or door or to maintain it in closed position and this plate 25 is also provided with an aperture 20 through which a padlock or the like may be inserted to lock the door. The spring latch, however, is not the sole means for maintaining the door in closed position for the reason that I have 30 provided a novel handle for operating the switch which will later be described and which maintains the door shut so long as the parts of the switch are closed.

The inner faces of the longitudinal walls 35 18 and the back or rear wall are respectively provided with sheets 10^a, 11^a, and 14^a of insulating material, which sheets are also fire-proof so that the arcing or sparking incident to the making or breaking of contact between 40 the switch elements is not liable to ignite portions of the structure within the housing or box or adjacent thereto.

As will be seen in the drawings, the non-movable parts of the switch are mounted 45 adjacent the juncture between the back wall and the longitudinal walls 10 and 11. In this connection I provide a plurality of supporting bases which are shown in detail in the drawings. Each base consists of an attaching plate member 21 which is secured to the back wall 14 of the box by screws, rivets or otherwise, and it has a laterally disposed portion 22 that is bifurcated in order to provide a guide slot 23 in which a reciprocating 50 55 bar is guided as will hereinafter more fully appear. The fixed contacts of the switch are mounted upon the outer edge of the laterally disposed portion and each consists of an L-shaped piece of metal the larger arm 60 65 65 of which bridges the recess or guide slot 23 and is seated in the groove 25 in the outer edge of the lateral member of the base. This contact element is secured to the supporting base by means of nuts and bolts 26 and its laterally disposed arm 27 is positioned near

the adjacent side wall 10 (or 11) of the housing or box and provides the switch tongue or blade that is engaged by the movable element of the switch. The slot 23 which bifurcates the supporting base is thus bridged by the stationary or fixed contact member of the switch.

The conductor wire 28 is connected to the long arm 24 of the fixed switch member by means of a terminal element having a tubular end portion 29 into which the wire conductor is inserted and held, and also has a laterally extending flat portion 30 that is placed upon the arm 25 prior to tightening the nut which secures the structure upon the base.

In order to protect and guard the live parts of the switch, and to insure against accident when the housing or box is opened, I have provided a protector for said parts which consists of a shell cast from "bakelite" or other insulating substance. The protector consists of a main portion 31 of concavo-convex cross-section that arches the arm 24 of the fixed contact and its securing bolts and nuts 26 as well as the flat lateral portion of the terminal. At one end, preferably the end next the tongue or blade, the shell or protector has a laterally extended portion that is likewise concavo-convex in section and extends along the side of the base and encloses the tubular portion 30 of the terminal as well as the adjacent portion of the conductor wire 28 in the manner shown in Figs. 5 and 6. At the other end of the protector the shell has an extension 33 that projects in the opposite direction to the extension 32 and is of rectangular shape in section and slightly wider than the other portions of the protector so that it encloses the tongue 27 of the contact and fits against the wall of the box. One side wall of this extension 33 is omitted or slotted to provide an entrance aperture 34 which permits the movable contact member of the switch to enter the protector and engage the arm 27 in the manner hereinafter described.

The protector is secured in position by means of a cap screw having an insulation head 35 and the shank 36 of which passes through an aperture 37 in the protector and is interiorly threaded so as to screw upon the projecting end of an adjacent bolt or screw 26 that secures the contact member terminal to the base. It will be seen that at all times the live members housed within this protector are guarded against contact by the hands of the operator and the protector may be readily removed for the purpose of inspecting or replacing any of the parts guarded thereby. In order however that the live parts of the switch may be tested without removing the protector I provide a hole 38 through which a proper instrument can be inserted whenever desired to make a reading.

The movable members of the switch are mounted upon elongated bars 39 that are arranged parallel to each other and are of rectangular section so that they will fit into 5 and be guided by the slots or bifurcations 23 in the bases as shown in Figs. 5 and 6. It will be seen that a plurality of the bases are mounted upon the back wall of the box alongside the adjacent side walls and the bars, 10 (preferably two), are mounted close to said side walls in the bases that support the stationary elements of the switch.

The bars are reciprocated by suitable means, to be hereinafter described, so that 15 they move simultaneously whenever the switch is operated. Notches 40 are formed in the outer surfaces of the bars 39 to receive the L-shaped metal bracket plates 41 each of which is L-shaped and has its lateral 20 member 42 disposed alongside the respective side walls of the housing. These lateral members each carries a pair of spring tongues 43 disposed parallel to each other and laterally to the bracket plate 41 and are each 25 slotted longitudinally to increase their resiliency. These spring tongues extend from their mounting plates or brackets in the direction towards the adjacent or fixed contact 30 blades 27 and the slotted portions 34 of the protectors or guards, and when the bars are moved in the proper direction these tongues 43 will enter the recesses 34 and slide into engagement with the blades 27 of the stationary switch contacts thus closing the 35 switch.

Secured upon the plates 41 of the brackets are spring yokes or U-shaped clips that are secured to the plates by the same means that connect the brackets to the bars and they 40 are in contact with said brackets so that when the fuses 45 are placed in these clips or yokes the circuit will be formed through said yokes, the brackets, and the tongues when the latter are in contact with the blades 27 of the stationary portion of the switch.

The handle 46 is disposed upon the exterior of the housing or box and consists preferably of a piece of heavy-gauge wire that has a portion bent laterally to the handle 50 to provide a spindle 47 that extends through the side walls 10 and 11 of the housing to provide the fulcrum for the handle, as well as a pivot for part of the adjacent control mechanism. A coiled contraction spring 48 55 connects the spindle with the adjacent end of one of the bars 39 and acts as a recoil to prevent jarring of the bars and switch elements when the parts of the switch are moved out of contact or in a direction away from the spindle 47.

A U-shaped oscillatory member is mounted loosely upon the spindle 47 with the latter piercing its parallel lateral arms 49 and with its main portion 50 lying parallel with said 60 spindle, and the ends of the arms 49 are con-

nected by links 51 with the adjacent ends of the bars 39. The mechanism for moving the U-shaped member 49-50 consists of a casting of irregular shape that is bored axially to receive the spindle 47 and at its outer portion is provided with a notch or recess 52 in which the angle formed by the spindle and handle is positioned. The outer portion 53 of this casting is cylindrical so as to fit into a round opening in the wall 11 of the housing or box, and the portion of the casting within the box is conical shaped as at 54 with its base innermost, while projecting from the base of the cone-shaped portion is a pair of oppositely disposed parallel lugs 55. 70 These lugs are positioned to engage opposite edges of the adjacent arm 49 and the adjacent end of the body portion 50 of the U-shaped element when the structure is operated by the handle. When the handle is moved from one position to another these lugs will engage the operating member in the manner shown in Figs. 3 and 4 of the drawings and will rock the U-shaped member causing the reciprocation of the bars 39. 75

In order to create tension as well as to insure the absolute make and break of the switch elements I have provided the mechanism which will now be described. Intermediate the lugs 55 the casting is provided 80 with ears 56 between which is hinged a lug 57 to which a disk 58 is secured, and a plunger rod 59 projects from said disk. The opposite end of the plunger rod passes through an aperture 60 in the lateral member 61 of 85 an L-shaped bracket 62 that is secured to the adjacent portion of the housing wall 11. Interposed between lateral member 61 and the disk 58, and surrounding the plunger rod 59, is a heavy coiled expansion spring 100 63. When the plunger rod 59 is upon either side of the plane intersecting the spindle 47 and the aperture 60 the spring will push against the disk and will cause the ear 56 to be moved in one direction or the other, 105 thus forcing the lugs 55 against the proper portions of the U-shaped operating member and moving the bars 39 in one direction or the other. In Figure 3 of the drawings the spring 63 is shown as expanded and the ear 56 is below the plane intersecting the spindle 47 and the aperture 60, and the movable parts of the switch are out of contact with the fixed parts. In Fig. 4 the spring 110 63 is shown contracted and in the position just at the time it is exerting its full power, which will maintain the switch parts in positive contact after they have been moved into engagement. Thus it will be apparent that the switch parts are maintained in their positions by means of the spring 63 and its contacting parts are in either a fully opened or a fully closed position, and it is practically impossible to stop the movement of the parts at an intermediate point. Because of 115 120 125 130

the fact the U-shaped operating member is loose on the spindle 47 and there is a slight play or looseness between the handle and the notch or recess 52, the action of the spring 63 causes a rapid snapping of the switch when being either opened or closed, thus making a quick contact or brake.

In order to maintain the door 15 against being opened while the parts of the switch 10 are in "on" position, the outer end of the handle has a lateral outwardly bent portion 64, which at its end is bent downwardly and oblique to provide a grip member 65. On the adjacent edge of the door I secure an abutment element or stop 66 in the form of a metal casting that is arched or slotted between its ends as seen in detail in Figs. 1, 15 3 and 4. The handle portion 46 is positioned and operates adjacent the wall 11 of the box 20 and the hinged edge of the door and when the grip-member 65 of the handle is in a depressed position (Fig. 4), for the "on" position of the switch parts the handle portion 46 will lie against and in the path of movement of the abutment or stop 66 so that the door may not be opened. When, however, 25 the grip and handle have been moved to the position shown in Fig. 3 for the "off" position of the switch the handle 46 will be 30 out of the path of movement of the abutment and the lateral portion 64 will offset the grip 65 far enough from the box wall to permit the door to be opened and the abutment to clear the handle.

35 What I claim is:—

1. An electric switch comprising a support, insulating guides mounted thereon, fixed terminals carried by said guides and having contact blades, an apertured insulating housing 40 enclosing each terminal and blade, reciprocable members mounted in said guides, movable contacts carried by said members and coactable with said blades through the apertures in said housing, and means for moving said 45 members simultaneously.

2. An electric switch comprising a support, insulating guides thereon, fixed terminals carried by said guides, contact blades extending from said terminals, an apertured insulating 50 housing enclosing each terminal and blade, sliding bars reciprocable in said guides, movable contacts mounted on said bars, means for simultaneously moving said bars to cause said contacts to enter the housing apertures and 55 engage said blades, and conducting elements connecting the contacts on one bar with corresponding contacts upon another bar.

3. An electric switch comprising a support, two rows of alined guide structures secured 60 thereto and having apertures, reciprocable parallel bars slidably mounted in said guides, terminals enclosed in said guides, contact blades extended from said terminals and accessible through said apertures, contacts 65 mounted on said bars, and common means

for moving said bars, whereby to cause said contacts to enter said apertures and engage said blades.

4. An electric switch comprising a support, two rows of alined guide structures secured 70 thereto and having apertures, reciprocable parallel bars slidably mounted in said guides, terminals enclosed in said guides, contact blades extended from said terminals and accessible through said apertures, contacts 75 mounted on said bars, common means for moving said bars, whereby to cause said contacts to enter said apertures and engage said blades, and removable conductors forming bridges between the contacts on the respective 80 bars.

5. An electric switch comprising a support, a pair of bases mounted thereon opposite each other and each having a guideway, switch contacts mounted on said bases, conductor 85 terminals also mounted on said bases, slidable bars reciprocable in the respective guideways, switch contacts mounted on said bars and coactable with the contacts on the respective bases, means operatively connecting said bars, 90 and devices for moving said bars simultaneously.

6. An electric switch comprising a support, a base thereon having a guideway, a switch contact mounted on said base, a conductor 95 terminal also mounted on said base, an insulating guard covering and protecting said contact and terminal and provided with an aperture adjacent the contacts, a bar slidable in said guideway, and a switch contact carried by said bar and adapted, when moved therewith, to enter said aperture and engage the first-mentioned contact.

7. An electric switch comprising a rectangular housing, a pair of bases mounted thereon adjacent the longitudinal walls of the housing and each having a guideway, spaced slidable bars reciprocable in the respective guideways adjacent the respective walls a conductor terminal and switch contact mounted on each base, a fuse-clip and switch contact mounted on each bar, and means for reciprocating said bars simultaneously.

8. An electric switch comprising a support, a pair of bases mounted thereon and each having a guideway, slidable bars reciprocable in the respective guideways, a conductor terminal and switch contact mounted on each base, a fuse-clip and switch contact mounted on each bar, means for reciprocating said bars simultaneously, and insulating guards covering and protecting the structures mounted on the respective bases.

9. An electric switch comprising a rectangular housing, a plurality of fixed and movable contacts therein, a pair of spaced reciprocable parallel bars adjacent the longitudinal walls of said housing and to which said movable contacts are secured, and a plu- 120 125 130

rality of bases secured in the housing adjacent the longitudinal walls thereof in which bases said bars are slidably mounted and one of said fixed contacts secured to each base.

- 5 10. An electric switch comprising a support, fixed and movable contacts thereon, reciprocal bars to which said movable contacts are secured, and bifurcated bases arranged in spaced relation on said support, said fixed contacts bridging the bifurcations thereof and said bars guided in said bifurcations.
- 10 15. Signed at Chicago, in the county of Cook and State of Illinois, this 28th day of February, 1930.
